UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

HAND-LAMP SWITCH.

1,349,860.

Specification of Letters Patent. Patented Aug. 17, 1920.

Application filed November 11, 1919. Serial No. 337,149.

To all whom it may concern:

Be it known that I, ARTHUR L. STAPLES, a citizen of the United States, residing at New Haven, in the county of New Haven, 5 State of Connecticut, have invented certain new and useful Improvements in Hand-Lamp Switches; and I do hereby declare the following to be a full, clear, and exact description of the invention, such as will 10 enable others skilled in the art to which it appertains to make and use the same.

The present invention relates to portable electric lamps comprising a casing, a battery and an incandescent lamp mounted 15 therein, and a contact device on the casing by which the flow of current from the battery through the lamp may be controlled at will.

In a portable lamp of this character, it is 20 desirable that the user shall be able to flash the lamp, that is, light it for short periods of time, as in signaling, or for such length of time as it is convenient for the operator to hold his thumb on the contact device. It 25 is also desirable that means be provided for closing the switch to light the lamp for a longer period of time and without the need for continuous thumb pressure on the contact mechanism.

It is an object of the present invention 30 to provide a hand lamp with a contact mechanism so arranged that the lamp can be flashed or can be permanently lighted, as desired, but with the additional feature that 35 the contact mechanism can be locked in open-circuit position to prevent inadvertent closing of the switch through accidental pressure on the contact device. This permits the hand lamp to be carried about with 40 tools or in the pocket of an automobile door without the danger that when the lamp is needed its battery will be found exhausted because, through accident, the switch has been closed and the lamp has been lighted 45 without the knowledge of the user.

Other objects and advantages will become apparent from the following description, which is to be taken in conjunction with the accompanying drawings, wherein—

Figure 1 is an elevation of a hand lamp constructed in accordance with the present invention;

Fig. 2 is a longitudinal section on the line 2—2 of Fig. 1;

Fig. 3 is an enlarged detail of the contact device; 55

Fig. 4 is a longitudinal section on the line 4—4 of Fig. 3;

Fig. 5 is a transverse section on the line 5—5 of Fig. 3; 60

Figs. 6 and 7 correspond to Fig. 4 except that the sliding member is in different positions;

Fig. 8 shows the escutcheon plate and its 65 housing before assembly thereon of the movable elements;

Fig. 9 is a detail of the spring member, and

Fig. 10 shows the tangs on the sliding member and how they are bent to form a 70 locking lug.

In the embodiment illustrated, a casing 1 of fiber, or other suitable material, is provided at its bottom end with a threaded ring 2 on which is mounted a bottom cap 3 75 of metal carrying a coiled spring 4 which engages the naked bottom of the lowermost dry cell 5. The uppermost dry cell 6 has its inner or carbon electrode 7 in contact with the inner terminal of the lamp 8, and 80 the outer or threaded terminal of the lamp is connected, as through a reflector 9, with a conductor 10, which may be in the form of a flat strip, and leads to a contact device conveniently positioned near the middle of 85 the casing. The lamp is provided with a lens 11 held in position by a flanged threaded collar 12, having engagement with a threaded ring 13, mounted on the front end of tube 1. Preferably the periphery of 90 reflector 9 is insulated from collar 12 and ring 13 to prevent inadvertent lighting of the lamp when the hand lamp is laid down on a metal surface.

The contact mechanism comprises an es- 95 cutcheon 14 connected to the bottom of the lowermost dry cell 5, as through a flat strip 15, the upper end of which is riveted to the escutcheon and the lower end of which is tucked under and makes connection with the inwardly extending flange of ring 2 100 and so is in electrical connection with the battery through cap 3 and spring 4. Mounted on this escutcheon plate and preferably

integral therewith is a housing 16. Within this housing is a contact member 17 preferably in the form of a spring fastened to the housing at its lower end, as by means of a rivet 18, and movable at its upper end into and out of contact with a contact member 19, which may be an integral part of strip 10, or may in other ways be in electrical connection therewith and with the lamp. The spring member has a relatively large push button or thumb-piece 20 which is exposed at an opening in housing 16 but does not project appreciably above the outer face of the housing.

To facilitate assembly of the device, and adjustment of the width of the air gap at lug 19, the spring member 17 carries a spring finger 21 integral with thumb-piece 20 and folded back thereunder, as shown in Figs. 6 and 9. During assembly, this can be bent toward or away from lug 19, as occasion may require.

The structure above described can be manipulated by pressure on the thumb-piece 20 of the flexible spring member 17 to flash the lamp. The structure can be laid down on a flat surface without danger of closing the switch for the thumb-piece 20 is guarded by the encircling edge of the housing.

To permit the lamp to remain lighted without the need for continued pressure on the thumb-piece 20, there is provided a locking means comprising an auxiliary thumb-piece 22 with integral tangs 23 adapted to pass through slots 24 (Fig. 8) in housing 16 and then to be bent, as shown in Figs. 5 and 10, to form a lug 25 of special shape, as hereinafter described.

This lug projects into and through a slot 26 in spring member 17 (Fig. 9). The front end of lug 25 has a notch or recess 27 which, on forward movement of thumb-piece 22, engages the adjacent end of slot 26 and so locks the spring member 17 in open-circuit position. By having recess 27 slightly out of alignment with the opposing metal edge, the forward movement of thumb-piece 22 will crowd thumb-piece 20 outward against the housing, and so will put enough spring tension on the spring member 17 to prevent a too easy disengagement at notch 27. There is thus little likelihood of accidental unlocking through inadvertent backward pressure on auxiliary thumb-piece 22.

With the parts in the position shown in Fig. 4, the rear corner 28 of lug 25 strikes against the adjacent end of slot 26, and prevents the movement of thumb-piece 22 to the position shown in Fig. 6; but thumb pressure on thumb-piece 20 will so flex the spring member 17 that the rear corner 28 of lug 25 will clear the end of the slot and the lug can be moved to the position shown

in Fig. 6, where it serves to hold the spring element 17 in circuit-closing position and obviates the need for continued pressure on the contact device when the lamp is to be burned continuously. 70

Spring contact member 17 yieldingly holds the parts in the position shown in Fig. 6, while the lamp is being used, but does not prevent return of the auxiliary thumb-piece 22 to the intermediate position 75 shown in Fig. 4. It will therefore be understood that with the parts in the position shown in Fig. 4, the auxiliary thumb-piece 22 is locked against rearward movement and thumb-piece 20 can be freely manipulated to flash the lamp, and that when a permanent light is desired, the thumb of the operator can be wiped down across the thumb-piece 20 to unlock lug 28, and thereafter can slide auxiliary thumb-piece 22 85 into the position shown in Fig. 6, and the lamp will burn continuously. Or, if the lamp is to be packed away and lighting is to be avoided, the auxiliary thumb-piece can be moved from the position shown in 90 Fig. 4 to the position shown in Fig. 7, and not only will the spring member 17 be locked in open-circuit position, but the resiliency of that member will prevent inadvertent return of thumb-piece 22 to the position shown in Fig. 4. 95

I am aware that various changes may be made in the details of the present invention without departing from the spirit thereof, as defined by the appended claims. 100

I claim:—

1. A contact device for battery hand lamps, comprising a spring member having a push button manually operable to flex the spring-member into circuit-closing position, 105 and means manually movable into engagement with said spring member to lock said member in closed position or in open position as desired.

2. A contact device for battery hand lamps, comprising a spring member manually operable for instantaneous contact, locking means movable into engagement with said spring member to hold said member in closed position when a continuous 115 light is desired, said locking means being itself locked against movement until said spring member has been manually operated.

3. A contact device for battery hand lamps, comprising a spring member manually operable for instantaneous contact, and means movable in one direction to lock said member in closed-circuit position and movable in the other direction to lock said member in open-circuit position. 120

4. A contact device for battery hand lamps, comprising a leaf-spring having a thumb-piece by which it may be manually operated to flash the lamp, a sliding thumb-actuated member engageable with said 130

spring to hold it in circuit-closing position, said sliding member being locked against said sliding movement until after said spring member has been manually depressed.

5. A contact device for battery hand lamps, comprising a housing, a spring member fastened at one end to said housing and movable at its other end to close the circuit, and means movable along said housing into locking engagement with the outer face of said spring member when the circuit is to remain closed, and movable in the other direction into locking engagement with the inner face of said spring member when closing of the circuit is to be avoided.
10. A contact device for battery hand lamps, comprising a housing, a spring member secured at one end to said housing and having a push button at its other end manually operable to flex the spring-member and thereby close the circuit through the lamp, and a thumb-piece mounted to slide along said housing and carrying means engageable with said spring member to lock it in
15. open position when lighting of the lamp is to be avoided.

7. A contact device for battery hand lamps, comprising a housing, a spring member mounted therein and movable to close the circuit, a push-button for actuating said spring member and a thumb-piece mounted to slide in one direction along said housing and having means to hold the spring member in closed-circuit position, said thumb-piece being itself so shaped as to be locked by the spring member until after the spring member has been depressed.

8. A contact device for battery hand lamps, comprising a housing, a spring member secured thereto at one end and movable at its other end to close the circuit, and means carried by said housing and movable in one direction after depression of said spring member to hold said spring member in closed-circuit position, said means being so shaped that when moved in the other direction it will engage said spring member in its open-circuit position and lock it against movement when lighting of the lamp is to be avoided.

In testimony whereof I affix my signature.
ARTHUR L. STAPLES.
